UNITED STATES PATENT OFFICE

HENRY F. SCHMIDT, OF LANSDOWNE, PENNSYLVANIA, ASSIGNOR TO WESTINGHOUSE ELECTRIC & MANUFACTURING COMPANY, A CORPORATION OF PENNSYLVANIA

BLOWER

Application filed September 14, 1927. Serial No. 219,471.

My invention relates to vertical blowers, or compressors, of the propeller type, and it has for an object to improve the construction of apparatus of this character.

5 In apparatus of the class described, the driving motor and the propeller are usually supported from below by suitable foundation work, upon which the casing may also rest. With such an arrangement, considerably head room is required to permit removal of the casing, in order to gain access to the motor.

10 Furthermore, guide vanes are usually located between the motor and the propeller so that before access can be had to the motor, the propeller must be removed from above, after which the casing may be raised the desired amount to permit removal of the motor.

15 This procedure is objectionable because of the time and labor required and, in addition, blowing apparatus is often installed in positions which are inaccessible by cranes, and the like, which would facilitate assembling and dismantling.

20 More particularly, therefore, an object of my invention is to provide a blower, of the type described, which shall be so constructed as to permit the motor and the propeller to be removed as a unit, and in which this operation may be performed without disturbing the casing.

25 Apparatus embodying the features of my invention is shown in the accompanying drawings, in which:

30 Fig. 1 is a sectional elevation of a blower, showing a section through the casing on the line I—I of Fig. 2; and.

35 Fig. 2 is a section on the line II—II of Fig. 1.

40 According to my invention the entire blower is supported from above, and the guide vanes are located above the propeller, so that the motor and the propeller may be removed as a unit. Preferably, the motor and the propeller are suspended within the casing by means of suitable supporting members which also serve to reinforce the casing.

45 Referring now to the drawings for a better understanding of my invention, I show a vertical blower, indicated generally at 10, and

comprising a converging-diverging casing 11, in which a propeller 12 is disposed. A suitable motor, such as a turbine, or an electric motor 13, is disposed below the propeller and connected for operating the latter.

55 Extending longitudinally of the casing 11, and secured to the exterior thereof, are a number of channels 14, which are adapted by any suitable means, such as the gusset plates 15, to be secured at their upper ends to a supporting structure, as to the deck of a ship, and at their lower, or depending ends to carry a suitable framework 16, for supporting the motor and the propeller.

60 The framework 16 preferably takes the form of a suitable number of channels, or the like, 17, which extend transversely of the casing and are arranged to support the motor in any suitable manner, the channels 16 being supported at their outer ends by the depending ends of the channels 14.

65 In the arrangement shown, only two channels 17 are employed, and these are prevented from spreading by the tie plates 18, which are secured to the respective channels. The central portions of the channels and the tie plates are bent to conform to the contour of the motor. Suitable abutment means, such as the flange 20, is provided on the motor casing, and this flange is adapted to rest on 70 the channels 17, and thus, to transmit the weight of the motor and of the rotor elements of the blower to the channels 17. These channels 17 are secured at their outer ends to the lower, or depending ends of the channels 14.

75 In order to do away with the necessity of removing the propeller and motor as separate units, I dispose the guide vanes 21 and bearing 22 above the propeller and thus, by means of my supporting structure, I am able to remove the propeller and the motor as a unit by merely disconnecting the framework 16.

80 Also, since the casing only supports its own weight and that of the guide vanes, it may be made of relatively light sheet metal. The channels 14 also serve as stiffening members for a casing of this light material and hence, dampen vibrations and thereby provide, not only a rugged structure free from vibration, 85

90

95

100

but also free from any noise which might otherwise be produced by vibrations.

It will thus be seen that I have provided a simple, and yet rugged construction which provides for the proper alignment between the casing and the motor elements, and which facilitates dismantling and assembling of a blower of the type described.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:—

1. The combination with a blower comprising a convergent-divergent casing, a propeller within the casing, and a motor for operating the propeller, of a plurality of longitudinally extending members bent to conform substantially to the contour of the casing and secured thereto, and means for supporting the motor and the propeller from the depending portions of said longitudinally extending members.

2. A vertical blower comprising a casing, a propeller within the casing, a motor for driving the propeller, a plurality of members arranged outside of the casing and extending longitudinally thereof, said casing being secured to said members along co-extensive portions of said casing and said members, means for supporting the motor from the lower portions of said members, and means for attaching the upper portions of said members to a supporting means, whereby the entire organization may be supported from said supporting means by said longitudinally-extending members.

3. The combination with a blower comprising a casing, a propeller within the casing, and a motor for operating the propeller, of a plurality of members arranged outside the casing and extending longitudinally thereof and secured thereto, spaced channels extending transversely of the casing and secured to the depending portions of said longitudinally-extending members, said transversely-extending channels having their intermediate portions built to substantially conform to the contour of said motor, and abutment means on said motor and adapted to rest on said channels for supporting said motor.

4. The combination with a blower comprising a casing, a propeller within the casing, and a motor for operating the propeller, of a plurality of members arranged outside the casing and extending longitudinally thereof and secured thereto, spaced channels extending transversely of the casing and secured to the depending portions of said longitudinal-

ly-extending members, means for preventing said transversely-extending channels from spreading, and abutment means on said motor and adapted to rest on said channels for supporting said motor.

5. In vertical blower apparatus, the combination of a vertically-extending casing, a propeller disposed within the casing for effecting a forced circulation of air therethrough, a motor disposed below and connected to the propeller for driving the same, a bearing structure disposed above the propeller and secured to the casing for retaining the upper end portion of the connected motor and propeller in axial alignment with the casing, structural members extending longitudinally of the casing and provided in the vicinity of the upper end of the casing with attachment means, and means disposed below and extending transversely of the casing and connecting with the lower portions of the longitudinally extending structural members for supporting the propeller and the motor relative to the casing, said supporting means being so arranged as to provide for the withdrawal of the motor and the propeller, as a unit, axially and downwardly from the casing.

In testimony whereof, I have hereunto subscribed my name this 25th day of August, 1927.

HENRY F. SCHMIDT.
